UNITED STATES PATENT OFFICE.

LOUIS BURGER, OF CHICAGO, ILLINOIS.

DESIGN FOR A SPOON.

SPECIFICATION forming part of Design No. 22,253, dated March 7, 1893.

Application filed January 3, 1893. Serial No. 457,170. Term of patent 3½ years.

To all whom it may concern:

Be it known that I, LOUIS BURGER, a citizen of the United States, residing at Chicago, in the county of Cook and State of Illinois, have 5 invented and produced a new and original Design for Handles for Souvenir Spoons, &c., of which the following is a specification, reference being had to the accompanying drawing, illustrating my design.

10 The drawing illustrates a handle made after my design used in connection with the bowl of a spoon.

15 The leading feature of my design consists in the handle having upon it the representation of a divided shield with two adjacent faces, on each of which is the representation of the head and bust of a man, pendent from which shield are two United States flags with 20 staffs crossing and flags unfurled, the representation of the shield constituting the end or

head portion of the handle. The shield is shown as surmounted by the representation of an American eagle with wings outstretched and adjacent to the flags and between the representation thereof and the inner end of 25 the handle the shank portion has in part of its outline the form of a medallion, engraved or embossed with a picture of Columbus, and the shank portion between the medallion and the inner end has a scroll outline. 30

What I claim as new, and desire to secure by Letters Patent, is—

The design for the handle of a souvenir spoon &c. substantially as herein shown and described.

LOUIS BURGER.

In presence of—

J. N. HANSON,
W. N. WILLIAMS.
